UNITED STATES PATENT OFFICE.

AMOS F. BUMPUS, OF PRESCOTT, ARIZONA.

MAGAZINE PENCIL.

Application filed January 22, 1927. Serial No. 162,829.

This invention relates to pencils and particularly to pencils carrying relatively long leads, means being provided whereby the leads may be shifted through the pencil as the leads are worn.

The general object of the present invention is to provide a very simple and readily operable pencil of this character made of relatively few parts which cannot get out of order and whereby the lead may be positively projected whenever desired.

A further object is to provide a pencil of this character having a magazine whereby the leads may be carried.

15 My invention is illustrated in the accompanying drawings wherein:—

Figure 1 is a longitudinal sectional view of a pencil constructed in accordance with my invention;

20 Fig. 2 is an elevation of the lead guide; Fig. 3 is an end view of the lead guide;

Fig. 4 is an end view of the expeller; Fig. 5 is an end elevation of the thimble;

Fig. 6 is an elevation thereof; Fig. 7 is an elevation of the grooved tube;

Fig. 8 is an elevation of the magazine; Fig. 9 is an end view thereof;

Figure 10 is a sectional view illustrating a modified form of the magazine.

30 Referring to these drawings it will be seen that the pencil consists of a central, longitudinally slotted, lead guide 10. Disposed within this lead guide is the expeller 11 which fits the bore of the lead guide and which at its rear end is convoluted so as to form a plurality of fins 12 to extend through the longitudinal slot 13 of the guide 10. The forward end of the lead guide 10 is slightly contracted as at 14, and its forward 40 end extends through a thimble 15 which has an enlarged rear end 16 and a relatively contracted forward end 17 which snugly fits the lead guide and is formed with a lug 18 which fits the slot of the lead guide. Disposed over the forward end of the lead guide and over this thimble 15 is a barrel 19 which has formed integrally with it the tapering tip 20. This tip may be held to the flanged end 16 of the thimble by indenting the barrel at intervals, as at 21, and correspondingly indenting the flange 16 so that thus the thimble and the barrel are held to each other for simultaneous rotation.

Surrounding the lead guide 10 is a spirally 55 grooved tube 22 which fits within the thimble

15 and this tube at its forward end is circumferentially indented, as at 23, and the thimble is also correspondingly indented, as at 24, so that the thimble and the spirally grooved tube will have rotative engagement 60 with each other but be held from relatively longitudinal movement. The rear end of this spirally grooved tube is formed with an outwardly projecting lug 25. Disposed within the barrel 19 is a tubular member 26 65 formed with a flange 27 at its forward end. The exterior face of this member is longitudinally fluted, as at 28, so as to form a series of longitudinal compartments for the leads and constitute with the barrel a magazine. The inner wall of the upper portion of the member constituting the magazine is longitudinally slotted, as at 29, for a distance not quite the full length of the magazine, and the lug 25 operates in this slot. 70 The unslotted portion of the tubular member 26 prevents the member from being pulled entirely off of the part 22.

Disposed within the extremity of the tubular members 26 is the contracted end 30 80 of an eraser holder 31 which is of a size to snugly fit within the barrel 19. The contracted end 30 of this eraser holder is held to the tubular members 26 by indentations 32. An eraser 33 is held within a socket in the eraser holder and this eraser is normally covered by a cap 34 which fits the exterior of the eraser holder. Preferably the eraser 33 is disposed within an enclosing cap 35 which is tapered and thus the cap portion 90 35 may be turned outward if desired and the cap 34 need not be used. In this form of pencil, the lead will be fed or expelled outward by turning the eraser holder to the right. This, of course, will act to force the expeller longitudinally towards the point of the pencil. A reverse movement of the eraser holder will cause the expeller to move rearward and permit the insertion of a new point. The tubular member 26 is preferably 100 tapered towards its forward end so that when the member 26 is withdrawn, the leads will be presented in a flared or relatively divergent relation. When a new lead is desired from the magazine, the eraser holder 105 is pulled outward. This pulls the tubular member outward upon the spirally grooved member 26 and thus presents the leads where they can be conveniently secured.

While preferably the extremity of the lead 110

guide will be slotted and slightly contracted so as to frictionally hold the lead from falling out, yet it may be desirable under some circumstances to longitudinally slit the point 5 or tapering end of the portion 20 which will frictionally engage the lead and prevent its dropping out.

In Figure 10 I have illustrated a modified form of magazine which differs from the 10 magazine previously described only in that the corrugations or flutes 28^a are formed in the outer wall of the magazine so that the magazine includes an outer wall or barrel, the inner face of which is longitudinally 15 corrugated instead of an inner wall the outer face of which is corrugated. This provides a wider space between the outer portions of the leads, permitting a better separation by the ridges of the corrugations, which is a 20 valuable feature in case of very thin leads. Furthermore, this type of magazine can be very readily manufactured and the corrugations would also serve to strengthen the walls of the barrel.

25 I claim:—

1. A pencil of the character described including a centrally disposed, longitudinally split lead guide, an expeller disposed within the lead guide and having a fin extending out through the slot, a helically grooved member surrounding the lead guide and with the groove of which the fin engages, an outer barrel having a tapered extremity formed with a bore registering with the lead guide, a thimble disposed within the tapered end of the barrel and engaged therewith and supporting the forward end of the lead guide and having 30 rotative engagement with the forward end of the tubular threaded member, a magazine surrounding the tubular threaded member, the magazine and threaded member having one a groove and the other a lug engaging in the groove, and a head mounted upon the outer end of the magazine and by which the magazine may be rotated or pulled out from the barrel, and a cap engaging over the head and closing the end of the barrel.
2. A pencil of the character described including a centrally disposed, longitudinally

split lead guide, an expeller disposed within the lead guide and having a fin projecting out therefrom through the slit thereof, a helically grooved tubular member surrounding the lead guide and with the grooves in which the fin engages, a barrel having a tapered extremity, the extremity being bored to register with the lead guide, a thimble disposed within the tapered end of the barrel and having an extended rear end engaged with the barrel and supporting the forward end of the lead guide, the helically grooved tubular member having swiveled engagement in said thimble, a magazine disposed over the helically grooved member and having rotative engagement therewith but adapted to slide longitudinally thereon, and a head disposed within the barrel and engaged with the magazine for common rotative movement and longitudinal movement.

3. A pencil of the character described including a longitudinally split lead guide, an expeller operating therethrough and having 35 a fin projecting out through the slot, a helically grooved tubular member surrounding the lead guide and with the groove of which the fin engages, an outer barrel having a tapered extremity formed with a bore registering with the lead guide, a thimble disposed within the tapered end of the barrel and engaged therewith and supporting the forward end of the lead guide and having 40 rotative engagement with the forward end of the tubular threaded member, a magazine surrounding the tubular threaded member, the magazine and threaded member having one a groove and the other a lug engaging in the groove, and a head mounted upon the outer end of the magazine and by which the magazine may be rotated or pulled out from the barrel, and a cap engaging over the head and closing the end of the barrel.

In testimony whereof I hereunto affix my signature.

AMOS F. BUMPUS.
